ATTORNEY.

UNITED STATES PATENT OFFICE

125,281

DESIGN FOR A CHENILLE BEDSPREAD

Ben Lombard, New York, N. Y.

Application November 23, 1940, Serial No. 96,759

Term of patent 3½ years

To all whom it may concern:

Be it known that I, Ben Lombard, a citizen of the United States of America, residing in New York city, county of New York, and State of New York, have invented a new, original and ornamental Design for a Chenille Bedspread, of which the following is a specification, reference being had to the accompanying drawing, forming part thereof, wherein,

The figure is a plan view of a chenille bedspread showing my new design.

I claim:

The ornamental design for a chenille bedspread, substantially as shown.

BEN LOMBARD.
